UNITED STATES PATENT OFFICE.

JOH. BLAUKOWITCSH, OF ALLENTOWN, PENNSYLVANIA.

WIRE ARTICLE.

Application filed August 5, 1927. Serial No. 210,767.

This invention relates to wire articles with particular reference to such as are made of net-work construction, capable of being twisted, folded, collapsed or extended into a multiplicity of shapes or forms.

One of the objects of this invention is to provide a wire article which may be receptive of various commodities and which when empty may be folded substantially flat so as to take up very little space.

A further object is in the provision of an article of the class described which is of pleasing appearance, can be cheaply constructed and is useful for innumerable purposes.

These several objects, together with others, which will become apparent as the description progresses, are attained by the novel construction, combination and arrangement of elements, hereinafter described and illustrated in the accompanying drawings, forming a component portion of this disclosure, and in which:—

Figure 1 is a side elevational view of a wire article made in accordance with this invention, as shown in an extending portion.

Figure 2 is a top plan view of the same.

Figure 3 is a fragmentary enlarged view showing the manner in which the top portion of the device is constructed.

Figures 4, 5, 6 and 7 are enlarged fragmentary views illustrating a few portions into which the elements forming the wire basket may be shaped.

In the drawing, the numeral 10 generally designates a roll of scallops, each of which includes a plurality of concentric wires having hooks 11 at their upper ends, engageable with a circular bent wire 12, from which extend upwardly, a plurality of single semi-elliptical wires 13.

Engageable with the wires 13 through their wire links 14 are similar semi-elliptical wires 15 having their open ends hooked to engage larger but similar over-lapping wires 16, the upper open ends of which are looped to en-

gage a band wire 17 similar to but larger than the wire 12.

Fastened to the wire 17 are a plurality of triply formed semi-circular wires 18 comprising the upper row or layer.

The entire device is constructed of thin, flexible wire and, as can be obviously seen, folded or bent into any number of ordinary and ornamental shapes.

When extended as shown in Figure 1, the row of wires 16 may be receptive of any desired commodity, such as fruit, large nuts, or other edibles.

From the foregoing, it will be further noted that when the device is completely collapsed, it will present a very thin article, taking very little space for storing purposes.

While the foregoing is descriptive of the preferred embodiment of my invention, similar forms may be constructed without the exercise of invention or conflicting with the spirit of the claims hereto appended.

Having thus described my invention, what I claim as new and desire to secure by Letters Patent, is:—

1. A wire article comprising a plurality of scallops, each scallop including a plurality of concentric loops of different radii, bands connecting the ends of said loops, said loops extending outwardly to serve as supports, a plural series of loops engaging said band and connected to a second band, and a final series of scallops, each scallop including a plurality of concentric loops of different radii extending outwardly from the last named band to constitute a unitary article.

2. In a wire article, a plurality of scallops, each scallop comprising a plurality of concentric wire loops of different radii, a wire band engaged at the ends of said loops, and a super-structure of connected wire loops engaged with said band.

In witness whereof I have affixed my signature.

JOH. BLAUKOWITCSH.
